UNITED STATES PATENT OFFICE.

WILLIAM J. KIBBY, OF NEW YORK, N. Y., ASSIGNOR TO SPACESAVING APPLIANCE COMPANY, A CORPORATION OF NEW YORK.

WATER-HEATER.

1,018,711.

Specification of Letters Patent. Patented Feb. 27, 1912.

Application filed March 24, 1911. Serial No. 616,558.

To all whom it may concern:

Be it known that I, WILLIAM J. KIBBY, a citizen of the United States of America, residing at New York city, borough of Brooklyn, county of Kings, and State of New York, have invented certain new and useful Improvements in Water-Heaters, of which the following is a specification.

My invention relates to water heating apparatus and comprises certain improvements on a particular form of apparatus now on the market in which a plurality of water containing pipes run through a plurality of steam pipes, and the unequal expansion and contraction of the two sets of pipes under temperature variations automatically control the supply of steam to the steam pipes. While the system referred to is most efficient and satisfactory in general operation, its weakest point is the difficulty of maintaining steam tight joints at the numerous stuffing boxes in the steam header through which the water pipes extend to an exterior water header. My invention avoids this difficulty and also increases the efficiency of the apparatus as a whole by substituting a water header inside of the steam header, for the exterior water header heretofore used, and by having one common discharge pipe extend from said water header through a single stuffing box in the side of the steam header.

The best form of apparatus at present known to me embodying my invention is illustrated in the accompanying sheet of drawings in which,

Figure 1 shows a side elevation of a heater with parts broken away, and Fig. 2 is a detail modification showing a flexible diaphragm.

1 is the steam header, 2 the steam supply pipe connected therewith, and 3 a valve in pipe 2. The stem 4 of this valve is pivoted to one end of lever 6. An adjustable spring 5 is also connected to said lever near the same end, and has a pivoted connection to the valve casing. From one side of the steam header 1, extend a plurality of parallel steam pipes 7, 7, which, as shown, are screwed into the header, though they might be otherwise fastened. The other ends of these steam pipes are connected to the steam compartment 9, of the compound header 8, by expanding the ends of said pipe into plate 24 on said header, or by any other

convenient method. As shown this compound header is composed of the box section 23, having the covering plate 24 bolted to it (thus forming steam compartment 9 with steam outlet 10) and the second box section 25, bolted to the other side of section 23, and forming the water compartment 11, provided with water inlet 12. Into the partition 14, in the compound header, (formed by the bottom of box section 23) are fastened the ends of a plurality of water pipes 13, 13, which extend through the steam pipes 7, 7, being of lesser diameter, and projecting from each end thereof. If these water pipes are connected at one end to water header 16, inside of steam header 1, by ordinary screw joints as shown, their other ends can be conveniently fastened to partition 14 by internally and externally threaded nuts 15, 15, which screw on to the pipes and into threaded openings in the partition.

The whole construction of the compound header serves as a means for holding the set of steam pipes and the set of water pipes, in rigid relation each to the other, at one end, while they are left free to move one over the other at all other points.

From the outer side of the water header 16 extends a short outlet pipe 17 which passes through a stuffing box 18 on the outer side of the steam header 1. On the flange 19 on pipe 17, is mounted the slotted ear 20, which engages pin 21, on the end of lever 6, which lever is fulcrumed to the steam header 1 by adjustable connection 22. Such being the construction, the general principle of operation is that normally steam flows through valve 3, and pipe 2 to header 1, and thence through pipes 7, 7, to steam compartment 9 of header 8, from which it is discharged as wet steam or water of condensation through outlet 10. Cold water, passing through inlet 12 to water compartment 11 of compound header 8, flows through water pipes 13, 13, to water header 16, and then out through common discharge pipe 17, absorbing heat from the steam so that it issues as hot water. When the flow of water is stopped, so that the water in the pipes 13, 13 becomes overheated, said pipes also become heated and expand considerably, being usually made of brass. The steam pipes 7, 7, being usually made of steel and maintained at approximately

constant temperature by the steam passing through, or trapped in, them, do not contract or expand appreciably. As a result, the heating of the water pipes moves the water header 16 toward the outer side of the steam header 1, and projects the single discharge pipe 17 farther through stuffing box 18, moving lever 6, compressing spring 5 and closing valve 3. When water is drawn off and the incoming cold water contracts pipes 13, 13, the water header moves back, the valve 3 is opened by spring 5, and the flow of steam for heating purposes is resumed.

15 In the modification shown in Fig. 2, an annular flexible diaphragm 26, fastened at its outer circumference to flange 27 on steam header 1, and at its inner edge to flanges 28, on pipe 17, takes the place of stuffing box 18.

20 The advantages of my invention lie in the fact that but one stuffing box or flexible diaphragm does the work of the eight stuffing boxes which would be employed in a heater of this type constructed on the plan employing an external water header, and in the further fact that the efficiency of the heater is increased, as the water header now becomes a part of the heating surface, while in the other construction, it is a wasteful, 30 heat radiating surface, cooling the water passing through it, instead of helping to heat said water, as it does in my construction.

Various changes could be made in the 35 details of construction illustrated herein without taking the modified construction outside of the scope of my invention, so long as the principles of operation above described are retained.

40 Having, therefore, described my invention, I claim:

1. The combination of a plurality of parallel metal steam pipes, a water pipe of 45 lesser diameter formed of a metal having a higher coefficient of expansion when heated, located inside of each of the first mentioned pipes and fastening means holding the two sets of pipes in rigid relation at one end, a header connecting all the steam pipes at one 50 end, a second header of lesser diameter located inside of the first header and connecting all the water pipes together, inlet and outlet connections for the steam pipes and their header and for the water pipes and their header, a valve in the steam inlet and mechanism whereby the relative motions of the two headers open and close said valve.

2. The combination of a plurality of parallel metal steam pipes, a water pipe of 60 lesser diameter formed of a metal having a higher coefficient of expansion when heated, located inside of each of the first mentioned pipes and fastening means holding the two sets of pipes in rigid relation at one end, a 65 header connecting all the steam pipes at one

end, a second header of lesser diameter located inside of the first header and connecting all the water pipes together, inlet and outlet connections for the steam pipes and their header and for the water pipes and their header, a valve in the steam inlet and mechanism whereby the relative motions of the two headers open and close said valve, 70 said mechanism comprising a projection from the water header extending through an opening in the steam header, and a lever pivoted on the steam header, and connected to the projection from the water header and to the valve.

3. The combination of a plurality of parallel metal steam pipes, a water pipe of 80 lesser diameter formed of a metal having a higher coefficient of expansion when heated, located inside of each of the first mentioned pipes and fastening means holding the two sets of pipes in rigid relation at one end, a header connecting all the steam pipes at one 85 end, a second header of lesser diameter located inside of the first header and connecting all the water pipes together, inlet and outlet connections for the steam pipes and their header and for the water pipes and their header, a valve in the steam inlet and mechanism whereby the relative motions of the two headers open and close said valve, 90 said mechanism comprising a stuffing box in the side of the steam header, a pipe connected to the water header serving as an outlet therefrom and extending through said stuffing box, and a lever pivoted to the steam 95 header, and having one end connected to the said projecting pipe while its other end is connected to the stem of the valve controlling the steam inlet.

4. In a water heating apparatus the combination of a steam header, a water header 100 inside of the steam header and free to move therein, means for conducting steam into and out of the steam header, means for conducting water into and out of the water 105 header, means for automatically moving the water header relatively to the steam header when the temperature of the water rises, and mechanism operated by such movement to shut off the flow of steam to the steam 110 header.

5. In a water heating apparatus the combination of a steam header, a water header 115 inside of the steam header and free to move therein, means for conducting steam into and out of the steam header, means for conducting water into and out of the water 120 header, means for automatically moving the water header relatively to the steam header when the flow of water through the header ceases, and mechanism operated by such 125 movement to shut off the flow of steam to the steam header, said mechanism comprising a valve in the steam inlet, an opening in the side of the steam header, a projection 130

from the water header extending therethrough, and connections from said projection to the valve stem.

6. In a water heater the combination of
5 a steam header, a series of parallel pipes
connected to one side of the header, a water
header inside of the steam header, a series
of pipes extending from the water header
out through the steam pipes, means for
10 passing steam into the steam header, and
means for conducting water into and out of

the water header together with a valve controlling the steam connection to the steam header, means for automatically moving the water header relatively to the steam header 15 when the temperature of the water changes, and mechanism operated by such movements to open or close said valve.

WILLIAM J. KIBBY.
